CLAIM

The ornamental design for a retractable cellular fabric with cells of a drooped configuration, as shown and described.

DESCRIPTION

FIG. 1 is a front isometric of the fabric of the present invention, the fabric having an inner drooped cell positioned within an outer drooped cell and with the fabric shown in an open condition.

FIG. 2 is a left side elevation of the fabric as shown in FIG. 1 with the right side elevation being a mirror image.

FIG. 3 is a front elevation of the fabric as shown in FIG. 1.

FIG. 4 is a top plan view of the fabric of FIG. 1.

FIG. 5 is a rear elevation view of the fabric of FIG. 1.

FIG. 6 is a bottom plan view of the fabric of FIG. 1.

FIG. 7 is a front isometric of the fabric of FIG. 1 shown in a closed condition; and,

FIG. 8 is a left side elevation of the fabric as shown in FIG. 7 with the right side elevation being a mirror image.

A front elevation of the fabric as shown in FIG. 7 is identical to that shown in FIG. 3

A rear elevation view of the fabric as shown in FIG. 7 is identical to that shown in FIG. 5.

A top plan view of the fabric as shown in FIG. 7 is identical to that shown in FIG. 4.

A bottom plan view of the fabric as shown in FIG. 7 is identical to that shown in FIG. 6.
